UNITED STATES PATENT OFFICE.

HARRY W. WILLIAMS, OF DAYTON, OHIO, ASSIGNEE TO THE SUPERIOR TOOL COMPANY,
OF DAYTON, OHIO.

COOLING APPARATUS FOR LARD-DISPENSING MACHINES.

1,341,603.

Specification of Letters Patent.

Patented May 25, 1920.

Application filed March 25, 1918. Serial No. 224,602.

To all whom it may concern:

Be it known that I, HARRY W. WILLIAMS, a citizen of the United States, residing at Dayton, in the county of Montgomery and State of Ohio, have invented certain new and useful Improvements in Cooling Apparatus for Lard-Dispensing Machines, of which the following is a specification.

This invention relates to a water circulating system for lard dispensing machines, such as is shown, and described in United States Letters Patent No. 1,068,153, granted to W. R. Mittendorf, July 22, 1913. The machine of the aforesaid patent is designed and constructed for dispensing lard in retail quantities from the container in which it is placed by the packer. It has been found, owing to the variations in temperature that the lard becomes too soft in the summer months and too hard during the colder months of the winter season, to be handled by the means shown and described in said Letters Patent. In other words, the condition of the lard within the container must be neither too soft nor too hard in order to be properly acted upon by the means employed in said patent for removing the lard from the container. It is therefore the object of the present invention to provide a cooling circulating system around the lard in the container and the passage from the container to the point of discharge from the apparatus.

In the accompanying drawings so much only of the lard dispensing machine is shown to enable a description of this cooling apparatus in connection therewith. Referring in general terms to the drawings, Figure 1 is a side elevation of the body or upper portion of the machine in which the lard container is inclosed and the spiral conveyer which feeds the lard from the container to the discharge spout. Fig. 2 is a vertical sectional elevation on the line 2-2 of Fig. 1 of the body of the dispensing machine or upper portion of the machine in which the lard container is inclosed, the lard container being shown in section also. Fig. 3 is a vertical section view on the line 3-3 of Fig. 4 of the lower portion of the body and the portion therebelow which houses the spiral conveyer. Fig. 4 is a horizontal sectional view on the line 4-4 of Fig. 1. Fig. 5 is a horizontal sectional view on the line 5-5 of Fig. 1. Fig. 6 is an elevation

looking on the interior of the water jacket showing the water inlet and outlet. Parts of the two sides of the jacket are broken away on each side of the hinges. Fig. 7 is a horizontal view on the line 7-7 of Fig. 6. Fig. 8 is a detail view illustrating the feed disk.

In a detailed description of the invention similar reference characters indicate corresponding parts in the several views of the drawings.

The lard vending machine in its entirety has not been illustrated in the accompanying drawings because many of the details thereof are not involved in the present improvements. The stand upon which the lard container frame-work is supported is not shown, nor is the means for operating the pressure disk which removes the lard from the container shown, nor the means for operating the spiral conveyer which discharges it from the machine shown. All of these features as well as other elements peculiar to the lard dispensing machine are shown and described in the patent hereinbefore referred to. The portions of the apparatus in which the lard is contained is what concerns us here as it is with these portions the present improvements have to do. As shown in Fig. 2 the lard container 1 is supported in an inverted position on a bowl or lower receptacle 2, said bowl being supported on three or four legs 3 as may be desired. The pressure or feed disk 4 in the body of the lard within the container 1 feeds the lard down into the bowl 2 and from there the spiral conveyer 5, which lies within the bowl 2, feeds it out through the discharge spout 6 into the delivery cup 37. The pressure disk 4 is attached to a connecting rod 7 and this connecting rod and the spiral conveyer are both driven from the same source of power as is clearly shown and described in the patent hereinbefore referred to. The disk 4 is enabled to cut its way through the lard owing to the auger-like slot 4' therein as shown in Fig. 8.

It will be understood that the whole interior of the apparatus as shown in Figs. 2 and 3 is always full of lard. This is especially true of the bowl 2 and the discharge spout 6. The container 1 is discharged of its contents during the operation of the machine but there is always some lard therein until the last portion is removed therefrom.

into the bowl or lower receptacle 2. As each lard container is emptied by the disk 4 a new full one is placed in the machine with the mouth down and the disk is driven 5 through the lard therein until it reaches the bottom of the can, or the top when the can is in position as shown in Fig. 2, as is fully described in the patent hereinbefore referred to.

10 I will now proceed to describe the water circulating systems or passages which surround the lard in the body of the machine or container and also the lard in the bowl 2 around the screw conveyer, and in the 15 discharge spout 6 and delivery cup 37. Referring to Figs. 1, 2 and 6, 8 designates the inlet pipe through which water passes under pressure from the source of supply, for example, the city main. The water supplied 20 to the hood passes through a T or two-way fitting 15 which discharges on both sides into flexible pipes 9—9 which connect to nipples 10—10 that communicate with the lowermost water channel 11 in the hood 25 parts. The hood consists of two sections or parts A—B, each of semi-circular form. The rear vertical edges thereof are shown in Fig. 6 to be united to bars 12 which lie on the exterior thereof. The ends 13 of the 30 said bars turn out and receive a pipe 14 which forms the pivot of the hinges or parts 13. The front vertical edges of the hood come together when closed and are held closed by any suitable means such as a 35 spring catch (not shown). It will be understood that the members A—B of the hood open to permit the empty lard cans to be removed and filled ones placed in the machine. I have specified that the flexible pipes 9—9 40 enter the bottom water spaces or channels 11 in the hood members. From these bottom water channels the water passes upwardly into water channels 16, 17, 18. These water channels are formed by a series of partitions 45 19, it being understood that the hood members A and B are formed each of two walls as shown in Fig. 2 between which the distance pieces or partitions 19 are secured. The water passes from one channel to the other 50 through passages 20 which are at opposite ends of the partitions, see Fig. 6 where two of such passages appear. When the upper channels 18—18 are filled the water passes out through flexible outlet pipes 21—21 55 which connect with nipples 22—22 in the upper portion of the inner walls of the hood members, see Fig. 7. It will be understood that the pipes 9 and 21 are necessarily flexible on account of it being necessary to open 60 and close the two members of the hood. The upper flexible pipes 21—21 connect with a Y-fitting 23 which connects with a down outlet pipe 24 which passes down through the pipe 14 which as hereinbefore stated 65 forms the pivot for the hinges 13—13 of the

two hood members A and B. The outlet pipe 24 is shown in broken lines in Fig. 1. The lower end of the pipe 14 is connected with a waste pipe 25 by an elbow pipe 26. As is apparent in Figs. 2 and 4, there is a 70 thorough circulation of water maintained around the lard container 1, which is essential, as before stated, in order to keep the lard in a proper state of firmness. The bowl or lower receptacle 2 is partially maintained 75 at the desired temperature through the conductivity of the metal. Around the margin of said bowl a water circulating channel 27 is formed. As hereinbefore specified the bowl 2 is always supplied with lard which is fed therefrom into the discharge spout 6. Referring to Fig. 6 the main water inlet pipe 8 continues above the T-fitting 15 in an extension 8'. This extension 8' connects with the water circulating channel 27. The water 80 from channel 27 circulates through a nipple 28 (Fig. 3) into a channel or water space 29, which entirely surrounds the discharge spout 6 which, it will be understood is always full of lard from the conveyer 5. The water in space 29, when it fills up, passes 85 into a channel 30 along the lower side of the spout 6, and into a rectangular water channel 31 in the bottom of the bowl 2, shown in broken lines in Fig. 5. The water enters 90 the channel 31 from the channel 30 through a nipple 32, and the channel 31 exhausts through an outlet connection 33 that discharges into the main waste pipe 25. The discharge cup 37 is hinged to the top of 95 the spout 6 as is more fully disclosed in the patent hereinbefore referred to. It is swung around out of alignment with the spout to discharge its contents. The said cup also 100 has a water jacket or space 38 which receives the circulating water from the spout water space 29 through a flexible pipe connection 39. The space 38 discharges into the spout outlet channel 30 through a flexible pipe connection 40. From the foregoing description 105 it will be seen that the parts containing the lard and the passages through which it is fed are wholly inclosed by cooling channels or spaces.

As hereinbefore stated the pressure disk 4 and the spiral conveyer 5 are driven by the same power. The power is conveyed directly to the conveyer by a crank handle 34 which is shown broken off in Fig. 3, and from the shaft of the conveyer the 110 power is conveyed through a chain 35 (which is also broken off in Fig. 3) to the rod 7 through intervening drive mechanism which is fully disclosed in the patent hereinbefore referred to.

Having described my invention and the manner of its use, I desire to claim:

1. A cooling means for lard dispensing machines comprising a hood inclosing a lard container in said machine, said hood 115

- having a series of inter-communicating water circulating passages therearound, a water supply pipe communicating with the initial water passages of said hood, through 5 flexible water connections between said supply pipe and said initial circulating passages.
2. A means for maintaining the lard in a lard dispensing machine in a proper condition 10 to be intermittently discharged therefrom, comprising a hood consisting of two hinged parts which inclose a lard container, said hood so constructed having a series of inter-communicating water circulating 15 passages throughout the interior thereof, a main water inlet pipe communicating with the initial passages in said hood, and an exhaust pipe communicating with the final water passages of said hood.
- 20 3. A cooling device for lard dispensing machines comprising a hood constructed of two parts having a hinge connection and a series of inter-communicating water passages on the interior thereof which extend 25 throughout the length of the hood, a main water supply pipe, flexible pipe connections between said main water supply pipe and the initial passages of the hood, an exhaust pipe, and flexible pipe connections between 30 the final water passages in said hood and said exhaust pipe.
4. A cooling apparatus for lard dispensing machines comprising a hood adapted to open and close around a lard container, 35 said hood having inter-communicating water passages extending throughout the interior thereof, a receptacle below the lard container adapted to receive the lard therefrom, said receptacle having water cooled 40 passages, a main water inlet pipe, and connections between said water inlet pipe and the water passages of the hood and lower receptacle respectively, an exhaust pipe, and connections between said exhaust pipe and 45 the passages in the hood and the receptacle below the lard container respectively.
5. In a device for maintaining a lard dispensing machine sufficiently cool for intermittent discharge of lard from the machine, 50 a hood inclosing a lard container in the dispensing machine, said hood having a series of inter-communicating water passages throughout the interior thereof, a receptacle below the lard container which 55 receives the lard therefrom and which has
- water passages therein, and a discharge spout communicating with said receptacle adapted to receive the lard therefrom, said discharge spout having a surrounding water passage which communicates with the water 60 passages of the receptacle.
6. In a device for maintaining the lard in a lard dispensing machine in a condition which admits of its intermittent discharge therefrom, a hood formed of parts having 65 a hinged connection, and inter-communicating water passages on the interior thereof, a receptacle below the hood having water passages therein, a discharge spout communicating with said receptacle having a 70 water passage inclosing the spout which is fed through an inlet from one of the water passages in the said receptacle, the water passage of said spout also discharging into another water passage in said receptacle, 75 and a water inlet pipe common to the water passages in the hood and the receptacle respectively.
7. In a cooling apparatus for lard dispensing machines, a hood inclosing a lard 80 container and having a series of water circulating passages therein to preserve the lard at the desired temperature, a receptacle below the hood and adapted to receive the lard from the container, said receptacle having water circulating passages 85 to preserve the lard therein at the desired temperature, a discharge spout having water circulating passages therein which communicate with those of the receptacle, an inlet pipe for supplying the passages of the hood and receptacle, and an exhaust pipe receiving the discharge from the hood and receptacle.
8. In a cooling apparatus for lard dispensing machines, a hood inclosing a lard container and having a series of water circulating 90 passages, a receptacle below said hood adapted to receive the lard from the container, said receptacle having water circulating passages, a discharge spout having water circulating 95 passages which communicate with the water circulating passages of the receptacle and a discharge cap on said spout having water circulating passages which communicate with those of the spout.
- In testimony whereof I affix my signature.

HARRY W. WILLIAMS.
